UNITED STATES PATENT OFFICE.

LUTHER E. JEROME, OF NEW HAVEN, CONNECTICUT, ASSIGNOR TO THE NEW HAVEN CLOCK COMPANY, OF SAME PLACE.

DESIGN FOR A CLOCK-CASE.

SPECIFICATION forming part of Design No. 16,901, dated September 14, 1886.

Application filed July 3, 1886. Serial No. 207,147. Term of patent 7 years.

To all whom it may concern:

Be it known that I, LUTHER E. JEROME, residing at New Haven, in the county of New Haven and State of Connecticut, have invented and produced a new and original Design for Clock-Cases; and I do declare the following to be a full, clear, and exact description of the same, reference being had to the accompanying drawing, which forms a part of this specification.

The accompanying drawing is a view in perspective of a clock-case containing my newly-invented design.

The leading feature of my design consists in a perforated and jeweled shell of curved surface.

A is a cylindrical shell, provided with a conical top, B, having a fluted or wavy edge, and furnished with a fluted cap, C, and a bail, D, the said shell and top being perforated, as at E, and set with jewels F, as shown. A ring, G, secured to the shell, carries the clock-dial

H, such ring being preferably secured to that portion of the shell forming the door of the case, which latter it is designed shall have an antique finish and receive a light.

What I claim is—

1. The design for a clock-case herein shown and described, the same consisting of a body in the form of an upright shell of curved surface, and having perforations and the ornamentation F, and also having a tapering top.

2. The design for a clock-case herein shown and described, the same consisting of a perforated and jeweled cylindrical shell having a conical top.

In testimony whereof I have signed this specification in the presence of two subscribing witnesses.

LUTHER E. JEROME.
